UNITED STATES PATENT OFFICE.

ABRAHAM SUDEROV, OF NEW YORK, N. Y.

CLUSTER-SETTING.

1,317,237.

Specification of Letters Patent. Patented Sept. 30, 1919.

Application filed July 3, 1919. Serial No. 308,583.

To all whom it may concern:

Be it known that I, ABRAHAM SUDEROV, a citizen of the United States of America, residing at New York, N. Y., have invented 5 a new and useful Cluster-Setting, of which the following is a specification.

My present invention relates to cluster settings, and the objects of the invention are to provide a setting of this character of 10 simple inexpensive construction, and in which the parts can be made up separately and be readily assembled as required.

A further and special object is to provide a cluster setting in which the top plate carrying the gems can be readily connected and disconnected with respect to the back member, thus enabling the gems to be transferred from one article to another, as from a scarf pin to a ring, for instance.

According to this invention, therefore, the top plate which is formed with seats for the 20 gems is made separate and distinct from the back member, and the two members are connected by a tubular connection which 25 preferably involves a screw threaded joint for enabling the ready attachment and detachment of such members. The details of the invention will be better understood by a consideration of the accompanying drawing, wherein the invention is 30 illustrated as embodied in one of its practical commercial forms.

In this drawing:

Figures 1 and 2 are plan and edge views 35 respectively of the top plate.

Figs. 3 and 4 are similar views of the back member.

Fig. 5 is a central sectional view of the 40 two members of the setting in assembled relation.

The top plate 7 which forms the base for the gems, is provided with suitable sockets or seats 8 for the jewels or gems, the number of these seats depending upon the number and size of stones to be set and the final shape of the cluster which it is desired to produce.

The back member consists of a series of radiating arms 9 inclining forwardly from 50 their points of attachment to the centrally disposed supporting stud 10.

The stud 10 is shown as of tubular construction and as centrally screw threaded at 11 for engagement with corresponding 55 screw threads on the interior of the tubular post 12 which projects rearwardly from the

central portion of the top plate. This tubular post 12 surrounds the central gem seat in the top plate as clearly indicated in Figs. 1 and 5, and the sides of the post 60 are preferably apertured as indicated at 13 to admit light to the back of the stone mounted in the central seat.

The interior of the tubular stud at the forward end thereof is shown as flared outwardly at 14 for the purpose of admitting as much light as possible and also providing a reflective surface at the back of the stone seated at the center of the cluster. The tubular connecting means described admits light through the cluster from the back, 70 and forms readily detachable means for firmly securing the two parts of the cluster together.

This invention, it will be seen makes it 75 possible to use the stones of the cluster with different articles of jewelry by simply unscrewing the top plate from the back member, which may be applied to one article of jewelry and transferring the same to the 80 back member on a different piece of jewelry. Thus, the same set of stones may be used at different times with different pieces of jewelry, and in each case when the top plate is applied to the back member the desired 85 artistic effect will be produced by reason of the coöperation of the radiating arms of the back member with the rim portion of the top plate.

I claim:

1. A cluster setting comprising a top plate provided with seats for gems and with a rearwardly extending substantially centrally disposed tubular post and a back member having a tubular stud engaged with 95 the tubular post of the top plate, and radiating arms extending forwardly from the central portion thereof to the rim of the top plate.

2. A cluster setting comprising a top 100 plate provided with seats for gems and with a rearwardly extending substantially centrally disposed tubular post and a back member having a tubular stud engaged with the tubular post of the top plate, radiating 105 arms extending forwardly from the central portion thereof to the rim of the top plate, said tubular post and stud having screw threaded engagement enabling ready attachment and detachment of the top plate 110 and back member.

3. A cluster setting comprising a stud

- having arms radiating from the rearward end thereof and extending forwardly and a top plate provided with gem seats and detachably connected with the stud aforesaid.
5. A cluster setting comprising a top plate and a back member, said top plate having gem seats therein and both said members having interfitting tubular portions for securing the members together.
10. 5. A cluster setting comprising a top plate and a back member, said top plate having gem seats and the back member having radiating arms extending from the central portion of said member forwardly toward 15 the rim portion of the top plate, and tubular means detachably connecting the central portions of said two members.
6. A cluster setting comprising a top plate provided with gem seats and with a 20 rearwardly extending tubular post, said
- tubular post having light openings in the side thereof, and a back member with which the tubular post of said top plate is engaged.
7. A cluster setting comprising a top 25 plate provided with gem seats, a back member provided with radiating arms coöperating with the rim portion of said top plate and means for detachably securing a central portion of said back member to the 30 central portion of said top member.
8. A cluster setting comprising a top plate provided with a central perforation and with gem seats disposed about said central perforation, a back member having radiating arms coöperating with the rim portion of said top plate, and a stud carried by 35 said back member and engaged in said central opening in the top plate.

ABRAHAM SUDEROV.
